US0D1030437S

(12) **United States Design Patent** (10) **Patent No.:** **US D1,030,437 S**
(45) **Date of Patent:** **** Jun. 11, 2024**

(54) **SHARPENING DEVICE**

(71) Applicant: **SENTOU INDUSTRY CO., LTD.,**
Yuanli Township, Miaoli County (TW)

(72) Inventor: **Tai-Yu Lee**, Taichung (TW)

(**) Term: **15 Years**

(21) Appl. No.: **29/866,331**

(22) Filed: **Sep. 8, 2022**

(51) **LOC (14) Cl.** **08-05**

(52) **U.S. Cl.**

USPC **D8/91**

(57) **CLAIM**

The ornamental design for a sharpening device, as shown and described.

DESCRIPTION

FIG. 1 is an upper perspective view of a sharpening device showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof; and,

FIG. 8 is a front view, showing the sharpening device in a condition of use.

The broken lines in FIG. 8 illustrate environmental matter and form no part of the claimed design.

1 Claim, 8 Drawing Sheets
